E. G. CLYMANS.
THRESHING MACHINE.

No. 597,458.

Patented Jan. 18, 1898.

By Attorney Robert M. Jenner.

Inventor
E. G. Clymans.

UNITED STATES PATENT OFFICE.

EZRA G. CLYMAN, OF WAYNESBOROUGH, PENNSYLVANIA, ASSIGNOR TO
THE GEISER MANUFACTURING COMPANY, OF SAME PLACE.

THRESHING-MACHINE.

SPECIFICATION forming part of Letters Patent No. 597,458, dated January 18, 1898.

Application filed November 12, 1896. Serial No. 611,831. (No model.)

To all whom it may concern:

Be it known that I, EZRA G. CLYMAN, a citizen of the United States, residing at Waynesborough, in the county of Franklin and State of Pennsylvania, have invented certain new and useful Improvements in Threshing-Machines; and I do hereby declare the following to be a full, clear, and exact description of the invention, such as will enable others skilled in the art to which it appertains to make and use the same.

This invention relates to threshing-machines; and it consists in the novel construction and combination of the parts hereinafter fully described and claimed.

In the drawings, Figure 1 is a longitudinal section through the rear portion of a threshing-machine constructed according to this invention. Fig. 2 is a detail plan view of a portion of the straw-shaker. Fig. 3 is a detail plan view of a portion of the cleaning devices. Fig. 4 is a detail longitudinal section through the tailings-shoe, drawn to a larger scale. Fig. 5 is a detail front and plan view of one of the notched quadrants. Fig. 6 is a detail front and side view of one of the levers engaging with the said quadrants.

A is a portion of the casing of the machine. The grain is threshed out at the front end of the machine by a cylinder and concave of approved construction. A' is a guard-board at about the middle of the machine. Rakes a deliver the straw over the top of the guard-board, and a' is a grain bottom or pan which extends under the cylinder and delivers the grain and chaff under the guard-board. All these parts are of any approved construction, but they are preferably constructed as shown in a separate application, filed February 17, 1896, Serial No. 579,546.

B is a crank-shaft journaled at the rear of the guard-board A' and provided with cranks b, arranged at opposite sides of its center so as to balance each other as much as possible. B' are teeth which project horizontally from the guard-board over the crank-shaft and prevent the straw from falling onto the cranks and becoming wrapped around the crank-shaft. A splash-curtain b', of flexible material, such as canvas, depends from the guard-board behind the rear end of the grain-bot-

tom and, together with the guard-board, prevents grain from flying rearwardly through the machine. The grain-bottom is vibrated by means of similar eccentrics C on the ends 55 of the crank-shaft B, and eccentric-rods C', driven by the said eccentrics and connected to the links c, which pivotally support the rear end of the grain-bottom. The eccentric rods and links are arranged outside the casing of the machine, and c' is a rod which is secured to the grain-bottom. This rod c' passes through slots in the casing and has its ends carried by the links c.

D is a rearwardly and downwardly inclined 65 deflector supported on ledges h in the upper part of the casing over the crank-shaft B. This deflector is preferably provided with a hinged extension D' at its lower end. This extension is normally supported by its hinges 70 d in the same plane with the deflector and it is free to move upward. The deflector is preferably formed of wood faced with sheet metal, and its upper end is pivoted to the casing by the rod d'.

E is a guard-block secured to the top of the casing to prevent the straw from sticking in the narrow space between the top of the casing and the deflector.

E' is a stationary return-bottom or gather-board supported in an upwardly and rearwardly inclined position in the upper part of the casing. Grate-bars F are supported above the return-bottom E'. The front ends of the bars F are carried by the guard-board A', 85 and their rear ends are secured to the cross-piece e' at the rear end of the return-bottom. The sides of the grate-bars are provided with ratchet-shaped teeth f, and their rear end portions are provided with bridge-pieces f', 90 arranged out of line with the grate-bars. These bridge-pieces clear the cranks b and are secured to the guard-board. The rear portions of the bridge-pieces extend downward, so that the lowest portions of the grate-bars are supported below the tops of the cranks when in their highest positions.

G are rakes provided with vertical teeth g on their upper edges and ratchet-shaped teeth g' on their rear end portions. The front ends 100 of the rakes are carried by the cranks b, and their rear ends are provided with upwardly

and rearwardly inclined bars G' , which slide in holes in the cross-piece e' . The rakes are provided on their under sides with projections or teeth h' .

5 The deflector presses the straw downward onto the straw-shaker, and the extension D' rises to let the straw pass under it. When the straw is discharged in dense masses, the whole deflector rises to let it pass onto the shaker. The rakes work the straw to the rear and shake out all the grain which is mixed up with it. The grain falls onto the return-bottom E' and is moved along it by the projections h' , so that the said return-bottom does not have to be shaken or placed at a steep angle.

10 The cleaning devices are arranged under the return-bottom E' .

H is the upper shoe, which receives all the grain and other material from the grain-bottom a' and the return-bottom E' .

H' is the lower shoe, which supports the grain plates or shelves. The rear end of the lower shoe is provided with two similar slots 25 i , which engage with pins i' , which project from the respective sides of the casing.

I is the upper cleaning-roll, and I' is the lower cleaning-roll. Both of these rolls are

30 journaled in the casing and are provided with grooves of any approved form. The upper shoe is provided with a comb J , arranged in front of the roll I , and the roll I is provided with cams j for the sides of the upper shoe to rest on. The cams j are preferably square.

35 The rear end of the upper shoe is pivoted to the lower shoe by pins j' .

K are similar slotted brackets secured to the upper shoe between the pivot-pins j' and the upper roll I , and k are pins which project from the lower shoe H' and normally rest on the bottoms of the slots in the brackets K , so that both shoes may be supported on the cams j and the pins i' . The cams j jog both shoes as the upper roll I is revolved.

40 L is the first grain plate or shelf supported by the lower shoe H' under the upper roll I , and L' is the second grain-plate supported in the shoe H' under the roll I' . These grain-plates have ledges k' on their front edges to 45 prevent the grain from sliding off them too freely.

M is a toothed comb secured to the first grain-plate in front of the lower roll I' , and M' is a toothed comb secured to the second grain-plate L' and projecting over the apex of the divider-bar m .

50 The divider-bar m is stationary and is secured to the casing A , so that it is not affected by the movement of the lower shoe. This 55 divider-bar is triangular in cross-section and has a plate m' secured to its substantially vertical front side and projecting below its bottom.

All three combs M' , M , and J are adjusted 60 simultaneously with respect to the divider-bar and the two cleaning-rolls by moving the shoes H and H' longitudinally in the casing.

The shoes are moved by means of two similar rods N , provided with pins n at their rear ends, which engage with notches in the lower shoe. The rear ends of the rods N are pivoted to similar levers n' , carried by a shaft N' , which extends crosswise of the machine-casing. A lever O is mounted on the shaft N' outside the casing and is provided with a catch o , which engages with notches o' in a quadrant O' , secured to the casing.

The shaft N' is preferably square or has a square end on which the lever O is loosely mounted. A pocket p is formed in the lever O , and p' is a spring which is inserted in the said pocket p and bears on the shaft N' , so that the catch o is forced into engagement with one of the notches o' . The upper end of the lever forms a pointer P , and the casing 85 is appropriately marked behind the pointer to indicate the position of the points of the combs. The lever is rocked on its shaft against the pressure of the spring to withdraw the catch from the notch before operating 90 the lever to turn the shaft and adjust the positions of the combs. The ends of the notched quadrant are provided with stops P' to prevent the lever O from being moved too far in either direction.

95 Q is a shaft extending crosswise of the machine under the first grain-plate L , and q is a lever on the end of the shaft Q outside the casing. The lever q is similar to the lever O and it engages with a notched quadrant in a 100 similar manner. Two similar cams q' are secured on the shaft Q , and when these cams are raised they lift the rear end of the lower shoe, so that it is no longer supported by the slotted brackets K . The lower shoe can be 105 raised, so that no jogging motion is imparted to it from the upper shoe by the cams j on the upper cleaning-roll, and this is very advantageous in cleaning some kinds and conditions of grain. More or less jogging motion 110 can be given to the lower shoe by varying the position of the cams q' and permitting only a part of the motion of the upper shoe to be communicated to the lower shoe.

115 R is the grain-spout, and S is the tailings-spout. Each of these spouts is provided with a conveyer of approved construction, such as a spiral auger-shaped conveyer, for discharging its contents.

120 R' is the tailings-shoe. The front end of this shoe rests on a cross-bar r , which forms a portion of the grain-spout, and its rear end is supported by pivoted links r' . These links have a rod s extending under the shoe R' , and they are pivoted to pins projecting from 125 the machine-casing.

130 A shaking motion is imparted to the shoe R' by means of two similar eccentrics s' and eccentric-rods t , which are connected to the rod s . The eccentrics s' are secured on the driving-shaft S' of the straw-stacker T , which is of any approved construction.

T' is a serrated plate secured to the shoe R' under the divider-bar, and t' is a removable

chaffer-riddle dropped into the shoe R' behind the plate T' and secured temporarily by any approved fastening device. The riddle t' is of any approved construction, such as 5 upwardly and rearwardly inclined slats having openings between them for the tailings to fall through. The riddle t' can be taken out altogether or other riddles having different sizes of openings may be substituted for it 10 according to the requirements of the material passing over it.

U is a serrated return-bottom or gather-board secured in the shoe R' and conducting everything that falls through the riddle t' into 15 the tailings-spout S.

U' is a screen or sieve of approved construction and preferably formed of perforated zinc. This screen U' is supported in the front part of the shoe R' in an inclined position under 20 the grain-plates L and L'. A return-bottom or gather-board u is connected by a hinge u' at its rear end to the shoe R' and its front end rests on a cross-bar v secured to the shoe.

V is a double-ended turn-button for holding 25 the bottom u down on the cross-bar v, so that the screenings which slide down it can pass off its front end and fall down the screenings-spout V'. When the screen is not required in use, the bottom u is raised and the 30 turn-button V is turned around so as to come above the cross-bar v and hold the bottom in its raised position.

W is the chamber for a fan or other similar device for supplying a blast of air to the cleaning devices.

W' is the blast-board, and w is the blast-passage.

The fan is of any approved construction.

Rotary motion is imparted to the crank-40 shaft, the two cleaning-rolls, and the straw-stacker shaft in the directions of the curved arrows by any approved driving devices, such as belt-pulleys secured on the ends of the respective shafts and rolls. A belt or belts 45 pass over these pulleys. These driving devices are not shown, as any approved driving devices can be used. The grain, chaff, or other material slides down the upper shoe and the grain forms piles on the grain-plates.

50 The good grain falls through the teeth of the combs and slides down the front faces of the piles of grain onto the screen U' in the tailings-shoe. The blast blows out the lighter chaff and the heavy rubbish is carried over the tops of the grooved cleaning-rolls. The lighter grains which fall on the rear side of the pile of grain on the first grain-plate are treated over again at the second grain-plate, and any good grain which passes over the second grain-plate is removed by the comb over 55 the divider-bar. The plate m' on the divider-bar causes one part of the blast to pass upward through the teeth of the comb M' and the other part to pass upward through the 60 chaffer-riddle. The chaffer-riddle removes 65 all the heavy rubbish and works it rearwardly

onto the straw-stacker. The screen U' removes the very small seeds and grains of dirt from the good grain before letting the grain pass into the grain-spout, and the provision 70 for closing this screen is made, because threshermen do not always consider it worth while to remove the fine seeds from the grain. The straight arrows indicate the direction of the blast passing through the cleaning de- 75 vices.

What I claim is—

1. In a threshing-machine, the combination, with a substantially vertical guard-board, and grate-bars having their rear ends supported by the guard-board; of a crank-shaft journaled under the grate-bars adjacent to the guard-board, rakes working between the said bars and operated by the said crank-shaft, and teeth secured to the said guard- 85 board above the said grate-bars and projecting over the said crank-shaft, substantially as set forth.

2. In a threshing-machine, the combination, with a stationary and substantially vertical 90 guard-board for stopping the flying grain, said guard-board being supported transversely in the middle portion of the casing; of rakes having their rear ends supported by the guard-board and operating to deliver the 95 straw over its top, and a straw-shaker provided with grate-bars having their front ends supported by the said guard-board, substantially as set forth.

3. In a threshing-machine, the combination, 100 with stationary grate-bars, of rakes provided with substantially vertical teeth at their front and middle portions, projecting ratchet-teeth at their rear portions, and bars G' at their rear ends; a stationary support for the bars 105 G' to slide on, and cranks operatively connected to the front end portions of the said rakes, whereby the straw receives the greatest tossing motion at the front ends of the rakes, and its rearward motion is accelerated when 110 it passes onto the ratchet-teeth at the rear ends of the rakes, substantially as set forth.

4. The combination, with an oscillatory shaft, of an operating-lever O free to lock longitudinally on the said shaft and provided 115 with a pocket p; a stationary toothed plate for the free end of the said lever to engage with, and a spiral spring arranged in the said pocket and bearing on the said shaft, whereby 120 said lever is normally held in engagement with the said plate, substantially as set forth.

5. In a threshing-machine, the combination, 125 with a grain-bottom, of a stationary and substantially vertical guard-board supported transversely in the casing behind and above the said grain-bottom, and a splash-curtain depending from the said guard-board behind the rear end of the said grain-bottom, substantially as set forth.

6. In a threshing-machine, the combination, 130 with a transverse guard-board, and a crank-shaft provided with cranks and journaled be-

hind it; of inclined grate-bars, bridge-pieces having their front ends secured to the said guard-board and extending over the tops of the cranks and supporting the lowest portions of the grate-bars below the tops of the cranks when in their highest positions; and rakes arranged between the said grate-bars and having their lower ends carried by the said cranks, substantially as set forth.

10. 7. The combination, with a lower shoe pivoted to the casing at its rear end and provided with grain-cleaning devices, of an upper shoe having its rear end pivoted to the lower shoe and provided with grain-cleaning devices, revoluble cams for jogging the upper shoe, and means for suspending the front end of the lower shoe from the upper shoe, thereby communicating to it the motion of the upper shoe, substantially as set forth.

15. 8. The combination, with two separate shoes each carrying portions of the grain-cleaning mechanism, of means for imparting a jogging motion to one of the said shoes, connections between the shoes whereby the motion of the

20. one may be communicated to the other, and adjusting mechanism operating to change the relative positions of the two said shoes thereby changing the extent of the motion imparted from the one shoe to the other, substantially as set forth.

25. 9. The combination, with two separate shoes each carrying portions of the grain-cleaning mechanism, the rear end of the lower shoe being pivoted to the casing, the rear end of the upper shoe being pivoted to the lower shoe, and the front end of the lower shoe being suspended from the upper shoe; of revoluble cams operating to support and jog both the said shoes, and adjusting mechanism operating to raise and support the front end of the lower shoe, thereby preventing the jogging motion of the upper shoe from being communicated to the lower shoe, when desired, substantially as set forth.

30. 10. The combination, with two separate shoes each carrying portions of the grain-cleaning mechanism, of means for imparting a jogging motion to the upper shoe, connections between the said shoes whereby the jogging motion of the upper shoe may be imparted to the lower shoe, and cams arranged under the lower shoe and operating to raise it out of operative connection with the upper shoe, substantially as set forth.

35. 11. The combination, with two separate shoes pivotally connected at their rear ends, each of said shoes carrying portions of the grain-cleaning mechanism, of connections between the said shoes permitting one or both of

them at will to be actuated, substantially as set forth.

40. 12. The combination, with a lower shoe pivoted to the casing at its rear end and provided with grain-cleaning mechanism, of an upper shoe having its rear end pivoted to the lower shoe and provided with grain-cleaning mechanism, slotted brackets secured to the upper shoe and engaging with pins projecting from the lower shoe, revoluble cams for supporting and jogging the free end of the upper shoe, and cams for raising the said pins of the lower shoe in the slots of the said brackets, substantially as set forth.

45. 13. The combination, with a reciprocatory tailings-shoe provided with a serrated plate at its front end, and a chaffer-riddle behind the said plate; of a divider-bar arranged above the said serrated plate and provided with a plate projecting below the front edge of the serrated plate and operating to prevent the blast from passing between the said serrated plate and the bottom of the divider-bar, substantially as set forth.

50. 14. The combination, with the grain-cleaning rolls journaled in the casing, and the stationary divider-bar carried by the casing; of toothed combs arranged in front of the said rolls and bar, a shoe supporting all the said combs, and means for moving the said shoe longitudinally in the casing thereby varying the distances of the said combs from the said rolls and bar simultaneously and to an equal extent, substantially as set forth.

55. 15. The combination, with a toothed comb, of a divider-bar triangular in cross-section and supported with one side substantially vertical and under the teeth of the said comb, and a plate secured to the said side and projecting below the bottom of the said bar, substantially as set forth.

60. 16. The combination, with a reciprocatory tailings-shoe, of an inclined screen for small seeds carried by the front part of the said shoe, a screenings return-bottom hinged at one end to the shoe under the said screen, a cross-bar secured to the shoe for the free end of the said return-bottom to rest on when lowered, and a double turn-button for securing the return-bottom to the said cross-bar or holding it in a raised position, substantially as set forth.

65. In testimony whereof I affix my signature in presence of two witnesses.

EZRA G. CLYMANS.
